United States Patent Office

Des. 217,798

Patented June 9, 1970

217,798

HUB FOR VELOCIPEDES AND THE LIKE

Frank T. Christian, Elmira, N.Y., assignor to The Bendix Corporation, a corporation of Delaware

Filed Jan. 21, 1969, Ser. No. 15,417

Term of patent 7 years

Int. Cl. D12—14

U.S. Cl. D90—12

Fig. 2

Fig. 1

Fig. 3

FIG. 1 is a side elevation view of a hub for velocipedes showing my new design.

FIG. 2 is a side elevation view of a modified form thereof.

FIG. 3 is an end view thereof.
The elements shown in broken lines are included for illustrative purposes only.

I claim:
The ornamental design for a hub for velocipedes and the like, as shown and described.
